SHOE CLAMP

Henry P. Stovall, Lake Charles, La.

Application March 2, 1944, Serial No. 524,743

3 Claims. (Cl. 12—123)

This invention relates to a shoe clamp.

It is primarily aimed to provide a means which will suitably hold a shoe, especially to facilitate the cleaning, polishing, or shining thereof, and is adapted for use generally as in hotels, homes, shoe shine parlors, depots, Pullman cars and the like.

It is particularly aimed to provide a structure which will enable the shoe to be rapidly clamped and released and which will facilitate the practice of leaving shoes with a bootblack or establishment for shining and can be called for at appointed times.

More specifically, it is aimed to provide a structure which is adjustable to clamp shoes of various sizes, and one which is collapsible so as to occupy minimum space when not in use.

The more specific objects and advantages will become apparent from a consideration of the description following taken in connection with accompanying drawings illustrating an operative embodiment.

In said drawings:

Figure 1 is a view in front elevation showing the clamp in use, with the shoe partly broken away to disclose details;

Figure 2 is a plan view of the clamp;

Figure 3 is a vertical section taken on the line 3—3 of Figure 1;

Figure 4 is a detail section taken on the plane of line 3—3 but showing only fragments of the clamp in a different position; and

Figure 5 is a detail section showing the swivel connection of the foot of the hold-down.

Referring specifically to the drawings wherein reference characters designate like or similar parts, I provide a suitable pedestal or support as generally designated 10. Support 10 mounts a long, relatively narrow table or shelf 11 adapted to support a shoe 12 or the like being cleaned or polished or shined. The shelf 11 has a socket 13 which is interiorly screw-threaded and detachably engaged with screw threads 14 at the top of the pedestal 10.

Directly over the pedestal 10 and socket 13, the shelf 11 has a transverse abutment 15 rising therefrom against which the breast of the heel of the shoe 12 is adapted to be disposed as shown in Figure 1.

At one end of the shelf 11, a rod 16 rises rigidly therefrom to any suitable height.

A suitable hold-down or clamp proper 17 is associated with the rod 16. This hold-down has a sleeve 18 which is vertically slidable on the rod 16 and rotatable thereon, as indicated by the

arrow line in Figures 4 and 2, respectively, as well as detachable therefrom. An arm 19, preferably rigid with the sleeve 18, extends horizontally therefrom in parallelism to the shelf 11 and a post 20 depends rigidly and preferably integrally, from such arm 19 so as to extend into the shoe 12 approximately in line with the pedestal. Post 20 has a foot 21 joined thereto by a ball-and-socket joint at 22 so that the foot may be suitably swiveled on the post to any angle to best engage the inner sole of the shoe as shown in Figure 1. The hold-down structure 17 is best manipulated through engagement with a knob 23 on the arm 19.

Attention is called to the fact that the bore of the sleeve 18 is slightly greater than the outside diameter of the rod 16, and hence when the two are engaged, their longitudinal axes are at a slightly angled relation to each other, whereby the sleeve 18 at diagonally opposite portions of the edges at its bore, will bite into the metal of rod 16 whereby the hold-down 17 will be held against slippage accidentally from the clamped position. Such hold-down 17 may be readily moved into and out of a shoe and swung on the rod 16 as an axis, when the hold-down structure 17 is held with the longitudinal axis of the sleeve 18 coaxial or parallel with the longitudinal axis of the rod 16. It will be noted that the heel of the shoe will be effectively held between the abutment 15 and the rod 16 as shown in Figure 1.

Various changes may be resorted to provided they fall within the spirit and scope of the invention.

I claim as my invention:

1. A shoe clamp of the class described comprising a shelf, a rod rising therefrom, means slidably and rotatably mounted on the rod engageable with the shoe to clamp the latter to the shelf, said means comprising a sleeve having a bore of greater diameter than the outside diameter of the rod to bite the latter in adjusted position, an arm extending from the sleeve, and a post depending from the arm to engage the shoe interiorly thereof.

2. A shoe clamp of the class described comprising a shelf, a rod rising therefrom, means slidably and rotatably mounted on the rod engageable with the shoe to clamp the latter to the shelf, said means comprising a sleeve having a bore of greater diameter than the outside diameter of the rod to bite the latter in adjusted position, an arm extending from the sleeve, a post depending from the arm to engage the shoe interiorly thereof, and an abutment on the shelf

between which and the rod, the heel of the shoe is disposable.

3. A shoe clamp of the class described comprising a shelf, a rod rising therefrom, means slidably and rotatably mounted on the rod engageable with the shoe to clamp the latter to the shelf, said means comprising a sleeve having a bore of greater diameter than the outside diameter of the rod to bite the latter in adjusted

position, an arm extending from the sleeve, a post depending from the arm to engage the shoe interiorly thereof, an abutment on the shelf between which and the rod, the heel of the shoe is disposable, said post having a foot swiveled thereon and directly engageable with the shoe, and a pedestal to which said shelf is detachably connected.

HENRY P. STOVALL.
